WILLIAM LOVELAND AND HARRY ELLWOOD SLOAN, OF PHILADELPHIA, PENNSYLVANIA.

PRINTER'S COLUMN-RULE.

1,123,772.

Specification of Letters Patent.

Patented Jan. 5, 1915.

Application filed April 1, 1914. Serial No. 828,893.

To all whom it may concern:

Be it known that we, WILLIAM LOVELAND and HARRY ELLWOOD SLOAN, citizens of the United States, residing at Philadelphia, in 5 the county of Philadelphia and State of Pennsylvania, have jointly invented a certain new and useful Improved Printer's Column-Rule, of which the following is a specification.

- 10 This invention relates to rules such as are used by printers in making up in a chase, columns of type or other matter. Such rules, as at present manufactured, are of one-piece construction provided with a short, thick V-shaped impression face and are generally unsatisfactory for the following reasons: Because of the great pressure exerted upon the contents of a chase when an impression is being made upon a mat 15 or matrix, either of the wet or dry variety, hardened steel rules are more lasting, but become corroded in use, due to moisture to which they are subjected. If non-corrosive rules, as for instance of brass, are used, 20 the metal being relatively soft, the impression face of the rule is useless once the impression edge becomes worn. Possibly a greater objection resides in the fact that the faces of rules as at present manufactured, 25 when used for impressions upon mats or matrices, either of the wet or dry variety, frequently fracture or otherwise mutilate or sever the fibrous material of the mats or matrices thus necessitating 30 the making of a new mat for casting purposes. Further it frequently happens that when impressions are being made, the body portion of the rule is embedded in a mat, thereby ruining said mat.
- 35 The principal objects of the present invention are to overcome the above described disadvantageous features and provide, first, a printer's column rule, which is practically efficient for the purposes intended and 40 which embraces features, whereby hardened steel impression members may be interchangeably fitted to non-corrosive rule bodies. Second, to provide a printer's column rule, the impression face of which is so de- 45 signed that desired impressions may be made upon mats without fracturing the fibrous construction thereof. Third, to provide such a rule so constructed that the rule-body acts as a stop to prevent same 50 being embedded in a mat.

With these and other objects in view, the invention consists of the improvements hereinafter described and finally claimed.

The nature, characteristic features and scope of the invention will be more fully 60 understood from the following description taken in connection with the accompanying drawings forming part hereof and in which:

Figure 1, is a view in side elevation of 65 a rule (exact size) embodying the invention. Fig. 2, is an end view thereof. Fig. 3, is a fragmentary view, partly in elevation and partly in section, drawn to an enlarged scale, of one end of the rule. Fig. 70 4, is a view in cross-section, drawn to a much exaggerated scale and illustrating the parts in position for being assembled, and Fig. 5, is a similar view of the parts assembled.

Referring now to the drawings in detail 75 10, designates the rule-body which in practice is usually brass, due in part to its non-corrosive character and also for the reason that it may be easily worked to provide for 80 the reception and holding in place of detachable impression faces to be presently described. One longitudinal edge of the body 10, is milled out throughout its length to provide a groove 11, to which is fitted a 85 continuous, very thin, hardened steel impression member 12. This member being very thin, the cross-section therof is very narrow and throughout the length of the member 12, and upon both sides thereof, 90 from its impression edge to about midway its height, said member is slightly tapered as at 13, to further reduce its cross-section and provide the desired impression face. As clearly shown in assembling the rule, 95 the tapered part of the member 12, extends slightly within the groove 11, of the body 10, so that this part of the member 12, is not closely hugged by the groove walls. To relatively interlock the parts together, 100 the rule-body upon both sides thereof and throughout its length is slightly depressed, as at 14, by suitable means, so that the groove walls are caused to closely hug that tapered part of the member 12, contained 105 therein, see Fig. 5. One end of the body 10, may be notched as at 16, immediately below and communicating with the groove 11, so that a suitable implement may be inserted to pry loose a worn member 12, so 110

that a new one may be fitted to place. As before stated, brass being relatively soft, new members 12, may be readily forced within the groove 11. By reason of the 5 very narrow, tapered cross-section of the member 12, the mats used to receive the desired impressions, readily accept such a member without having the fibrous mat texture fractured or otherwise mutilated as 10 frequently occurs by the use of the relatively broad faced rules now in general use. In this connection, it is to be further noted, that the flat top of the rule-body, at the parts designated 15, forms shoulders which 15 serve to act as stops to prevent the body cutting into a mat. By being able to replace worn impression members with new ones, the body portion of the rule may be used indefinitely, and since new impression 20 members may be readily fitted to place at little cost, a great saving and better work in printing is possible by the above column rule.

What we claim is:

1. A printer's column rule embracing a 25 body portion having a squared top edge, which top edge is longitudinally grooved throughout the entire length of said body portion, and a thin gradually tapered impression strip removably fitted to said 30 groove, the work end of said strip being projected an appreciable distance beyond the squared top edge of the rule, whereby at the juncture point of said squared edge and impression strip shoulders forming 35 stops are provided.

2. A printer's column rule embracing a body portion of relatively soft metal said body having a squared top edge, which top edge is longitudinally grooved throughout 40 the entire length of said body portion, and a thin impression strip of relatively hard metal removably fitted to said groove the work end of said strip being projected an appreciable distance beyond the squared top edge 45 of the rule, whereby at the juncture point of said squared edge and impression strip shoulders forming stops are provided.

3. A printer's column rule embracing a body portion having a square top edge, 50 which top edge is longitudinally grooved throughout the entire length of said body portion, and a thin gradually tapered impression strip removably fitted to said groove the work end of said strip being projected an appreciable distance beyond the squared top edge of the rule at least a portion of the tapered part of said strip being contained within said groove.

4. A printer's column rule embracing a 60 body portion of relatively soft metal the squared top edge of which is longitudinally grooved to removably receive a thin slightly tapered impression strip of relatively hard metal the work end of which is projected 65 an appreciable distance beyond the squared top edge of the rule at least a portion of the tapered part of said strip being contained within said groove.

5. A printer's column rule embracing a 70 body portion having squared bottom and top edges the upper squared edge being longitudinally grooved and a narrow slightly tapered impression strip removably fitted to said groove a portion of its tapered part 75 being contained within said groove and a portion thereof being projected above said squared top edge.

6. A printer's column rule embracing a rectangular body portion having squared 80 bottom and top edges the top edge being longitudinally grooved, to removably receive a slightly tapered, impression strip of a cross-section smaller than the body 85 cross-section, of which a portion of said tapered strip is contained within said groove and of which a portion thereof projects beyond the squared top edge of the body, whereby at the juncture point of said square edge and impression strip, shoulders or stops 90 are provided.

7. A printer's column rule embracing a body portion having squared bottom and top edges the upper squared edge being longitudinally grooved throughout its entire 95 length and a thin slightly tapered impression strip removably and snugly fitting said groove with at least a portion of said tapered part contained within the groove and the remaining tapered part projected above 100 the upper squared edge the side walls of the body being longitudinally compressed adjacent the body top to relatively interlock the impression strip with respect to the body.

8. A printer's column rule embracing a 105 body portion having a squared longitudinally grooved top edge at least one end of said body portion being notched immediately below and in communication with said groove and a thin impression strip removably fitted to said groove.

In testimony whereof, we have hereunto signed our names.

WILLIAM LOVELAND.
HARRY ELLWOOD SLOAN.
